UNITED STATES PATENT OFFICE.

EDWIN F. VAN VECHTEN, OF MILWAUKEE, WISCONSIN.

DISPLAY MECHANISM.

1,401,379.

Specification of Letters Patent. Patented Dec. 27, 1921.

Application filed January 10, 1920. Serial No. 350,537.

To all whom it may concern:

Be it known that I, EDWIN F. VAN VECHTEN, a citizen of the United States, residing at Milwaukee, county of Milwaukee, 5 and State of Wisconsin, have invented new and useful Improvements in Display Mechanisms, of which the following is a specification.

My invention relates to improvements in 10 display mechanisms, with particular reference to that class of mechanisms in which a series of signs, symbols, or samples, are intermittently or successively exposed to view for advertising purposes.

15 The objects of my invention are to provide means whereby a series of sets of overlapping signs, or advertisement carriers may be advanced and displayed in a predetermined sequence, by a single actuator,—to 20 provide means whereby each sign or carrier will be advanced from one set or group to the next when moved from display position, and in so doing will expose another sign which was previously concealed in such position,— 25 to provide for the advancement of each sign or carrier step by step along an endless line of travel, whereby each may be successively displayed in different positions and finally returned to the original starting 30 point, and to provide means whereby a continuously operating rotary motor, may actuate a carrier engaging member step by step, and adjust such member at regular intervals to release an advanced sign or carrier at the 35 rear side of a set or group, and subsequently readjust it in an advanced position to engage the next one to be advanced from that set or group, *i. e.*, the foremost one of the set.

40 A further object of my invention is to provide improved means for utilizing high speed motors such as electric or internal combustion motors, to develop relatively slow intermittent movements in a ratchet mechanism, which in turn is adapted to move the signs or sign carriers with the desired speed, and allow them to remain at rest for a considerable interval while others are being advanced and displayed at different points or stations along the line of travel.

45 Further my object includes the provision of means for supporting cardboard or other flexible signs in an upright position, and providing them with supporting members which also facilitate their manipulation or 50 advancement.

In the drawings—

Figure 1 is a view partly in vertical section and partly in elevation, of an advertising mechanism embodying my invention.

Fig. 2 is a plan view of the same, partly 60 in horizontal section.

Fig. 3 is a detail view of a fragment of the ratchet wheel and its actuating dog.

Fig. 4 is a view similar to Fig. 1 but showing a modified form of construction. 65

Fig. 5 is a plan view partly in horizontal section, of the form of construction shown in Fig. 4.

Fig. 6 is an enlarged fragment of the same 70 in horizontal section.

Fig. 7 is a plan view of a third form of construction showing my invention adapted for displaying signs in horizontal positions.

Fig. 8 is a fragmentary view on line 8—8 75 of Fig. 7.

Fig. 9 is a fragment in section on line 9—9 of Fig. 8.

Like parts are identified by the same reference characters throughout the several views.

In Figs. 1 and 2 the signs or sign carriers 80 are advanced along a circular path. Each comprises a sheet 1 of flexible material such as cardboard, provided along its front margin with a relatively thick rigid member or post 2. Its upper and lower margins run 85 between guide strips 5 and 6, 7 and 8 respectively, and its lower margin also travels along the surface of a supporting ring or platform 9. The posts 2 are preferably secured to the inner faces of the sheets along 90 their front margins and the guide strips are so spaced as to allow the sheets to be nested between them in sets, with their associated posts in contact in a series of sets or groups A, B, C, D and E. 95

Vertical walls 10 connect the outer top and bottom guide strips 5 and 7 opposite the sets or groups of posts and not only reinforce and support the structure of the frame formed by them and the guide strips, but 100 conceal the posts, and the margins of the sheets from view. The guide strips 6 are supported by cap ring or member 12.

The inner face of each post or bar 2 is provided with a notch or recess 14 which extends obliquely from its inner to its front face to allow an actuating hook 15 to engage the rear face of the next bar to advance the latter and its associated sheet 1 as hereinafter described. The shank of this hook is 110

pivoted at 17 to the outer end of an arm 18 which is rigidly connected with a ratchet wheel 20, disposed to revolve step by step in a horizontal plane about an axis at the center of the circular path along which the sheets 1 are guided. A spring 22 tends to swing the hook 15 outwardly into position for engagement in one of the notches 14. But an arcuate guide 25 is disposed in a position to engage a roller 26 carried by the hook shank and retract the hook as soon as it advances an engaged bar 2 to the group position from the rear side, including the advancement of the entire group the width of one bar, and the hook is then held in retracted position until it has been advanced into position for engagement with the front bar of the group, whereupon the roller 26 clears the front end of the guide 25 and spring 22 then causes the hook to engage such bar. A swinging movement of the arm 18 may then be utilized to advance the bar and its associated sheet 1 to the next group *e. g.* from group A to group B.

In order to promote the accurate positioning of the posts 2 and to prevent possible momentum effects when one carrier is advanced to the next group, I preferably provide the springs 27 which may be mounted upon the guide blocks or cams 25, in the position shown in Fig. 2. The shape and location of spring 27 is such that the bent end of each spring normally rests against the most advanced post in each series. When another carrier is added to the rear of the series, each post therein is moved forward the width of one post. Spring 27 is displaced by this movement and bears firmly against the foremost post, bringing it to a stop as soon as the actuating hook is withdrawn, and holding it in place where it will be engaged by said hook as soon as the roller 26 clears the cam block 25.

Power to actuate ratchet wheel 20 and arm 18 may be derived from any suitable source such as an electric motor 30. In the construction shown in Figs. 1 and 2 the motor shaft 31 transmits motion to the ratchet wheel 20 through the worm 32, worm wheel 33, shaft 34, worm 35, worm wheel 36, crank pin 37 thereon, connecting rod 38, swinging arm 39, and dog 40. The arm 39 is pivoted to the shaft of ratchet wheel 20, or otherwise supported to oscillate about its axis. The ratchet wheel 20 has notches 41 in its under surface in which the weighted dog 40 is adapted to engage, the weight 42 being adapted to hold the working end yielding against the under surface of the wheel. The arrangement is such that each stroke of the arm 39 will swing arm 18 through a sufficient arc to carry hook 15 from a position of engagement with one bar 2 into engagement with the one at the opposite end of the set or group and to then advance the newly en-

gaged bar into contact with the rear bar in the next set or group.

The advancement of the newly engaged bar as last above described, carries the exposed sheet 1 associated with it back of the next group of sheets and therefore conceals it while exposing the next sign or sheet in the group from which it was taken. This is accomplished for the reason that each successive sign or sheet 1 from the front of any given group is disposed at the inner side of the one which precedes it and therefore the removal of the foremost bar, takes with it the outermost sheet.

I preferably inclose the carriers (sheets 1) and their associated bars 2 within an annular transparent wall 45 secured to the inner faces of the rings 5 and 7 and to the inner faces of the opaque wall members 10. I also preferably employ guide members 6 and 8 of relatively thin material and notch or mortise the ends of the bars 2 to receive the margins of these guide rings 6 and 8 as clearly shown at the left hand in Fig. 1.

I also preferably extend the pivot shaft 17 vertically and provide the same with a plurality of hooks 15, each adapted to engage the same bar 2, the bars having a plurality of notches 14 at different elevations whereby the engaged bar may be pushed forwardly under pressure exerted near its top and bottom ends or above and below its center. Where a plurality of hooks 15 are employed, their shanks are preferably connected by a vertical rod 46 which, with the pivot post or shaft 17, connects up the hooks in such a manner as to form a substantially rigid truss whereby the shaft 17 may be maintained in a vertical position when supported in an elongated bearing 47 carried by the arm 18.

It will be understood from the above description and the accompanying illustration in Figs. 1, 2 and 3 that a large number of signs, symbols, or articles to be displayed may be mounted or printed upon the sheets 1 and arranged in groups of overlapping sheets or carriers from which group the display portions of the carriers may be exposed successively through the transparent portion of the wall 45, associated with such group by the withdrawal of the outermost carrier. Also that when a carrier is withdrawn from any given group, it becomes the innermost carrier of the succeeding group and will be subsequently displayed through the transparent portion of the wall 45 pertaining to that group, after the preceding carriers of that group have been successively withdrawn. Therefore, each carrier may eventually be displayed successively in connection with each and every group of the series.

By making the carrier sheets of such length that at least one sheet (the one pertaining to the rearmost carrier in a group) will over-

lap the bar of the foremost carrier of the next group to the rear, it is obvious that when my carrier is advanced it will necessarily be guided along the inner side or face 5 of the next group of sheets, no additional mechanism being required to accomplish this result. The terms "front" and "rear" are employed with reference to the line or direction of advancement on the assumption that 10 the movement is a forward movement.

Referring to Figs. 4, 5 and 6 it will be observed that the modification illustrated therein embodies the same general features as those above described and as illustrated 15 in Figs. 1 and 2, but that instead of following a circular path, the carriers are advanced along a line or path defined by the endless chains 50 extending over sprocket wheels 51 and 52 at the respective ends of the 20 structure. The structure disclosed in Figs. 4, 5 and 6 is so closely analogous to that disclosed in Figs. 1, 2 and 3 that the same reference characters are applied to the corresponding parts with the reference letter *a* 25 added for the purpose of distinction. Detailed description will, therefore, be unnecessary except to call attention to the following features, viz:

The hooks 15^a are pivoted to the respective chains 50 at 17^a and the rollers 26^a are carried on inwardly projecting arms 55 whereby the rollers are offset inwardly for engagement with guides 25^a which are also offset inwardly out of the paths of the 35 chains 50. And in view of the fact that there are two chains 50, one near the top and the other near the bottom of the structure, the hooks 15^a may be independently connected with the respective chains, there- 40 by dispensing with the elongated vertical shaft 17 and rod 46 disclosed in Figs. 1 and 2. The pivot pin 17^a is therefore merely a short pin and may constitute an elongated pintle serving to connect the chain links.

45 The motion transmitting connections between the motor and the driving sprocket wheels 51 are also somewhat different from those between the motor and the ratchet wheel 20 in Figs. 1 and 2. The motor 30^a 50 transmits motion to the driving sprocket wheel 51 through the motor shaft 31^a, worm 32^a, worm wheel 33^a, crank 37^a, connecting rod 38^a, swinging arm 39^a, dog 40^a, ratchet wheel 56 and driving shaft 57 connected 55 with the respective sprocket wheels 51. The result is quite similar to that above described (Figs. 1 and 2), each swinging movement of the arm 39^a being adapted to rotate the ratchet wheel one step and thereby 60 move the sprocket chains a distance sufficient to advance one carrier from a group or station to the next group or station, this operation being subsequently repeated for successive groups throughout the series, each 65 group also moving forwardly as described.

It is obvious that my invention can be thus applied, wherever space will permit, to display a series of signs or display carriers along a straight or substantially straight line simultaneously each sign or exhibit being exposed for a length of time equal to that required for shifting the other exposed signs, after which it moves to a place of concealment for a considerably longer period while other signs which were previously concealed are being exposed. The period of exposure may be shortened and the advancement of the signs or display carriers may be accelerated by providing the chains with additional hooks 15^a. Where two sets of 80 hooks 15^a and 15^a are employed two of the display carriers will be advanced from each group during one revolution of the conveyer composed of the set of chains and hooks.

Referring to the modification disclosed in 85 Figs. 7, 8 and 9, it will be observed that I have again used the same reference characters for the corresponding parts with the letter *b* added for the purpose of distinction, but in this form of construction, the display 90 carriers are horizontally disposed upon a platform 9^b having an annular opening spanned by the bars 2^b and the sheets 1^b which compose the carriers. The bars 2^b are disposed radially and the carriers travel in 95 a circular path.

The motor 30^b is mounted on a carriage 60 having an inner wheel 61 and outer rollers 62 and 63, the latter being adapted to follow a raised circular track 64 to which 100 they are held by the roller flanges 65. An endless cable 66 extends along the annular groove 67 formed in the outer wall of the track, and this cable extends about a pulley 68 carried by a vertical shaft 69 supported 105 in suitable bearings connected with the carriage 60. The motor shaft 31^b actuates the shaft 69 through the worm 32^b and worm wheel 33^b and as the shaft 69 revolves the cable continuously winds upon and unwinds 110 from the pulley, thereby propelling the carriage and the motor along the track.

A bracket 72 is connected with the top of the motor casing or frame and an oscillatory shaft 73 journaled in the bracket arms, is 115 provided with hooks 15^b which are adapted to engage the bars 2^b in the notches 14^b to actuate the foremost bar of each group, and deliver it to the next group in the same manner as above described with reference to 120 Figs. 1 and 2 except that the bars 2^b are radially disposed in a horizontal plane and the sheets 1^b are also horizontally disposed with their margins and portions of the ends of the bars 2^b resting in annular notches or runways formed in the outer and inner walls 75 and 76 between which the motor travels. The shanks of the outer hooks 15^b are provided with arms or projections which carry 125 rollers 26^b in positions for engagement with 130

guide strips 25^b which retract the hooks, after an engaged bar 2^b has been advanced from one group to the next and the receiving group advanced to a position where the 5 hooks may be permitted to engage the foremost bar thereof for advancement to the third group. The guides 25^b retract the hooks against the tension of springs 22^b, the entire principle of operation, so far as the 10 engagement and advancement of the signs or sign carriers is concerned, being similar to that in both of the forms of construction above described.

78 are brushes to electrically connect the 15 motors with circular conducting rails or wires housed within the track 64.

From the above description and the three forms of construction illustrated, it will be apparent that my invention is not dependent for successful operation upon the use 20 of any specific power transmitting or supplying mechanism nor upon any specific position of the sign or carrier, nor line of its advancement. It is sufficient for my purposes to provide means for grouping the 25 signs or sign carriers in overlapping relation and then provide means for successively advancing them so as to uncover them successively. But it is a very important 30 feature of my invention to provide successive groups, and to advance the signs or carriers in such a manner that the advancing member or its actuator will also advance the receiving group a distance sufficient 35 to maintain the position of the group, and present the foremost member thereof in a position to be engaged and advanced.

I claim—

1. Display mechanism including a drum 40 provided with a plurality of display openings, a group of carriers associated with each opening, display cards having their forward ends secured to the carriers, means for guiding said carriers circuitously about 45 the drum, and means moving from group to group for selectively actuating certain carriers, said cards being guided by overlapping carriers.

2. Display mechanism including a drum 50 provided with a plurality of display windows in its periphery, groups of carriers associated with each window, a track adapted to guide the carriers in a peripheral path, and display cards secured to the carriers, 55 each card being overlapped by succeeding cards and carriers.

3. Display mechanism including an apertured casing, a circuitous track therein, carriers upon the track and associated in groups 60 with each aperture, an actuator adapted to engage successively the foremost carrier in each group and add it to the rear of the next, and display cards mounted upon each carrier and adapted to be displayed by the 65 foremost carrier in each group, succeeding

carriers being adapted to guide preceding cards.

4. Display mechanism including an apertured case, a circuitous track therein, carriers associated in groups with each aperture and mounted upon the track for guidance thereby, cards mounted upon the carriers and disposed in overlapping succession along the wall of the case one card of each group being displayed through each 70 aperture, and an actuator adapted to engage successively the most advanced carrier of each of the several groups and add it to the rear of the next.

5. Display mechanism including a circuitous track, carriers mounted upon said track and grouped at predetermined points thereon, a uni-directional actuator adapted to engage the foremost carrier of each group and add it to the rear of the next, and a 80 resilient stop adapted to engage the foremost carrier of each group.

6. Display mechanism including a circuitous track, carriers grouped at predetermined points thereon, a resilient stop adapted to engage the foremost carrier of each group, a uni-directional actuator adapted to pass the several carriers of each group and engage the foremost carrier and add it to the rear of the next, thereby advancing said next group the thickness of one carrier whereby the foremost carrier of said last-named group is moved past 90 said stop into the path of the actuator.

7. Display mechanism including carriers 100 adapted to travel in a circuitous path and disposed in groups of even size at predetermined points thereon, an actuator operative to move the carriers about said path, means for retracting said actuator from 105 the path of the carriers to pass over a group of normal size, and a single extra carrier upon said path adapted when added to the rear of a group to advance said group sufficiently to bring the foremost carrier thereof into the path of said actuator, whereby each group in turn will become momentarily larger than the others.

8. Display mechanism including an apertured drum, carriers disposed in groups before each aperture, guides upon which the carriers are adapted to move in proximity to the periphery of the drum, overlapping display cards fastened to the carriers and each confined by succeeding carriers within the space between the guide and the drum, and a uni-directional actuator adapted to move from group to group in operative relation to said carriers.

9. Display mechanism including a number of groups of overlapping display carriers successively projected one beyond another at their front margins, means for engaging the front margin of the most advanced member of a group, withdrawing 125 130

it therefrom, and adding it to the next group, the addition of a new member to a group being adapted to move the entire group slightly whereby the most advanced member therein is forced to the position for removal.

10. Display mechanism including a group of overlapping display carriers, each comprising a sheet provided with a projection and arranged with the sheets successively advanced and with the projections correspondingly grouped, and an actuator continuously moving in one direction relative to said sheets and adapted to engage the 15 projections successively and to withdraw the sheets in succession.

11. Display mechanism including a plurality of display carriers disposed in groups with their front edges successively advanced 20 in accordance with the position of the carriers in the group, and an actuator adapted to add periodically one carrier to each group and pass over the intervening carriers thereof, to engagement with the foremost.

12. Display mechanism including a group of overlapping display carriers, each comprising a sheet provided with a bar along its front margin and arranged with the 30 sheets successively advanced from the exposed sheet inwardly and arranged with the bars in contact, and an actuator adapted to remove the bars successively from the group to withdraw the sheets, and means for utilizing the actuator to add a carrier to the group previous to each withdrawal, and to advance the group a distance equal to the thickness of the withdrawn bar.

13. Display mechanism comprising the 40 combination of a series of groups of overlapping display carriers, each comprising a display sheet having a bar along its front margin and arranged with the bars in series along a line of carrier advancement, and an 45 actuator adapted to engage the foremost bar and advance it to the next group and to utilize such bar to advance the next group a distance equal to its own thickness.

14. Display mechanism comprising the combination of a series of groups of overlapping display carriers, each comprising a display sheet having a bar along its front margin and arranged with the bars in series along a line of carrier advancement, and an actuator adapted to engage the foremost bar 50 and advance it to the next group and to utilize such bar to advance the next group a distance equal to its own thickness, means for retracting the actuator to allow it to travel across the group to a position for engagement with the front bar thereof, said actuator being adapted to advance the engaged bars successively from one group to the next.

15. Display mechanism comprising the 65 combination of a series of groups of overlapping display carriers, each comprising a display sheet having a bar along its front margin and arranged with the bars in series along a line of carrier advancement, and an 70 actuator adapted to engage the foremost bar and advance it to the next group and to utilize such bar to advance the next group a distance equal to its own thickness, means for retracting the actuator to allow it to 75 travel across the group to a position for engagement with the front bar thereof, said actuator being adapted to advance the engaged bars successively from one group to the next, and to eventually return them to 80 their original positions.

16. Display mechanism including a set of overlapping carriers with their front edges successively advanced, the foremost carrier being in display position; and an actuator 85 adapted to add periodically one carrier to the group and to pass over the intervening carriers to engagement with the foremost.

In testimony whereof I affix my signature in the presence of two witnesses.

EDWIN F. VAN VECHTEN.
